UNITED STATES PATENT OFFICE.

KAROP D. SENIOR, OF BOSTON, MASSACHUSETTS.

INDICATOR-LOCK.

1,146,737.

Specification of Letters Patent. Patented July 13, 1915.

Application filed August 20, 1914. Serial No. 857,785.

To all whom it may concern:

Be it known that I, KAROP D. SENIOR, a citizen of the United States, residing at Boston, in the county of Suffolk and State of Massachusetts, have invented new and useful Improvements in Indicator-Locks, of which the following is a specification.

This invention relates to improvements in indicator locks and has for its object to provide a lock particularly adapted for the inside of a door and to be operated only from said inside to lock and unlock said door, said lock having means arranged upon the exterior of said door adapted to indicate the locked and unlocked condition of said lock.

Another object of the invention is to provide means adapted to operate said indicator to indicate the condition of the room, that is to say, whether the room has been properly set in order or not.

Still another object of the invention is to provide a lock which is normally adapted to be operated to unlock the door only from the inside thereof, but which may in cases of emergency be operated from the outside thereof.

The invention consists in the combination and arrangement of parts as set forth in the following specification and particularly pointed out in the claims.

Referring to the drawings: Figure 1 is a front elevation of a lock and striker embodying my invention, portions of the casing of said lock being broken away to more clearly illustrate the same. Fig. 2 is a detail perspective view of the striker illustrating the manner in which it is to be attached to the door casing. Fig. 3 is a detail view of the bolt together with its operatively connected parts and the means for reciprocating said bolt. Fig. 4 is a section taken on line 4-4 of Fig. 1 as viewed in the direction of the arrows on said line. Fig. 5 is a detail perspective view of the slide. Fig. 6 is a section taken on line 6-6 of Fig. 4 illustrating the interior of the indicator casing.

Like numerals refer to like parts throughout the several views of the drawings.

In the drawings, 8 is the bolt casing which may be secured either to a door or a door casing preferably to the door "A" by means of screws 9, while to the other member is secured a striker 10 having a recess 11 adapted to receive the end of a bolt. The striker 10 is provided with ears 12 extending longitudinally thereof each adapted to receive a

screw 13. The face of the material constituting the striker is extended inwardly at 14 and is also adapted to receive a screw 15 which is secured in the face of the door jamb when the striker is secured to that part, or in the edge of the door when said striker is secured to the door, said screw 15 being entirely concealed when the door is closed thereby preventing the striker from being removed.

The lock in question is particularly adapted to be applied to either a right or left hand door and with very few adjustments. In the present instance the lock is arranged for a door which opens to the left on entering the room.

A bolt 16 is arranged to reciprocate in the casing 8 and is preferably a double ended bolt, the ends 17 and 18 thereof adapted to protrude from opposite ends of the casing 8 through holes 19 and 20 respectively in said casing.

A plate 21 is adapted to fit the inner side of the casing 8, which is the open side of the casing, and retains the bolt 16 in its proper position within said casing. The plate 21 and the front wall 22 of the casing are provided with cylindrical holes 23 and 24 respectively, said holes alining one with the other. Into these holes is inserted a cylindrical member 25, said cylindrical member having a lateral projection 26 which normally extends upwardly oblique to a vertical plane extending through the axis of said member 25. The projection 26 is adapted to extend into a recess or notch 27 in the bolt 16, said member preferably constituting the means whereby said bolt may be reciprocated or moved from its locked to its unlocked position or into and out of engagement with the striker 10. Pins 28 and 29 are provided in the casing 8 to limit the pivotal movements of said cylindrical member, said pins being engaged by said lateral projection.

A variety of means may be employed for rotating the member 25 such for instance as a thumb nut which may be secured thereon, but not shown in the drawings. One of the objects of the invention however is to provide a lock for the inside of a door by means of which the occupant of the room to which the same is attached may lock his door from the inside by means of the key which is made to fit the regular lock of the door, but accessible only from the outside thereof, the inner keyhole being plugged. For this rea-

son the cylindrical member 25 is arranged to receive the key adapted to lock the door from the outside. For this purpose the rotary member 25 is provided with a cylindrical hole 30 which constitutes an eye and a slot 31 extending from said cylindrical hole 30 downwardly and alining with a slot 32 formed in the front wall 22 of the casing, the pin 33 of the key being inserted in the cylindrical hole 30, while the web 34 of the key engages opposite edges of said member which constitute said slot 31 whereupon said cylindrical member may be rotated. As the key and the cylindrical member are rotated within the casing the web 34 of said key is moved out of alinement with the slot 32 and will be held by the front wall of the casing within the keyhole as long as the bolt remains in its locked position.

Operatively connected with the bolt 16, but preferably upon the opposite side of the door "A" from that upon which said bolt is arranged is an indicator 35, said indicator being adapted to indicate the positions of said bolt, that is to say, whether the same is in its locked or unlocked positions. The indicator preferably consists of a disk 36 arranged within a casing 37 to rotate upon a projection or pin 38 formed in said casing 37, said disk having upon its face a plurality of differentiating characters preferably consisting of segmental sections of different colored celluloid, such as red and white as at 39, 39 and 40, 40 respectively and secured in any suitable manner thereto. The face 41 of the casing 37 is provided with openings 42, 42 preferably diametrically disposed relatively to the axis of the disk 36, while the red sections 39, 39 are likewise oppositely disposed relatively to the axis of said disk and so are the white sections 40, 40, thus both red sections will be simultaneously displayed or both white sections will simultaneously be displayed according to the position of the bolt, the white sections preferably indicating the unlocked position of the bolt, while the red sections indicate the locked position thereof.

The casing 37 is secured to the outer side 50 of the door "A" as hereinbefore stated by means of screws 43 which extend through said door and from the inner side thereof, preferably from a plate 44 fast to said door, the inside of the casing 37 being open. As the bolt 16 is reciprocated in the casing 8 the disk 36 will be rotated by means extending through said door and preferably consisting of a flat key or connecting rod 45, one end of which is adapted to fit a transverse slot 46 formed in the disk 36, said key being detachably secured within said slot by a spur 47 extending from one side of the slot 46 through a hole 47' formed adjacent the end of said key. The opposite end of the key 45 is adapted to be in-

serted in one of a pair of slots 48, 48 arranged substantially at right angles to each other in the end of the hub 49 of a rocker arm or indicator tumbler 50 rotatably mounted in the bolt casing 8. The arm 50 is preferably slotted at 51 to engage a pin 52 carried by the bolt 16 hereinafter more specifically described. By this construction it will be seen that each time the bolt is reciprocated the disk will be rotated from one of its positions to the other. To assist in retarding the rotations of the disk 36 the same is yieldingly held in its position upon the projection 38 preferably by means of a curved spring 53, opposite ends of said spring engaging the rear face of said disk. The central portion of said spring is recessed at 54 to receive the hub of the disk 36, said central portion being also adapted to fit a recess 55 formed in the face of a plate 56 which is detachably secured at the rear of the casing 37 preferably by means of lugs 57 formed on said casing 37 and engaging depressions 58 in the adjacent face of said plate, said spring 53 being interposed between said plate and the disk 36 and prevented from rotating with said disk by the recess 55. In addition to indicating the extreme positions of the bolt 16, said indicator is adapted to display a different character which is for the purpose of showing the condition of that room, that is to say, whether the duties of the attendant in the room have been completed and this is adapted to be displayed only by means of a different key 59 which is adapted to be inserted in a keyhole 60 by said attendant. In the carrying out of this part of the invention a slide 61 is mounted to reciprocate on the bolt 16 preferably between lugs 62 and 63, and upon said slide the pin 52, hereinbefore referred to which engages the arm 50 in the slot 51, is formed. During the normal operation of the lock or at least when the bolt is moved from one of its extreme positions to the other, the slide 61 is moved therewith, a relative movement between said slide and said bolt at this time being prevented by a lever or tumbler 64 pivoted upon a screw 65 fast to said bolt and arranged preferably upon the opposite side of said bolt from said slide. The tumbler 64 has a projecting portion 66 which extends beneath said bolt to the opposite side thereof and is provided at said opposite side with a notch 67 which is adapted to receive a depending lug 68 formed on said slide, said projecting portion 66 being yieldingly retained in contact with said lug by a spring 69 one end of which engages a projection 70 on said tumbler 64. The opposite end of the spring 69 is secured to a lever 71 which is provided to engage the lateral projection 26 on the cylindrical member 25 and retain said cylindrical member 130

in its locked and unlocked positions. The end 72 of the projecting portion 66 is arranged to slidably engage the bolt 16 at 73 to guide said tumbler during its pivotal movements.

To operate the slide relatively to the bolt the key 59 is inserted in the keyhole 60 and the web thereof moved in the proper direction according to the position of the bolt to 10 engage said slide. Should the bolt be in the position indicated in Fig. 3 the key 59 will be rotated in the direction of the arrow "a", the web thereof engaging a face 74 at the right hand end of a recess 75 formed in 15 the slide 61, but before said slide may be moved by said key it is necessary to depress the tumbler 64, therefore said tumbler is also engaged by the web of said key along the straight portion 76 thereof which projects sufficiently to cause said projecting portion 66 of said tumbler to be lowered to 20 clear the depending lug 68. The tumbler is held in said lowermost position until the slide has been moved sufficiently to cause the end 83 thereof to engage the inner face 17' 25 of the end 17 of said bolt and withdraw the depending lug 68 from alinement with the notch 67. After the key has been turned completely around and the web thereof has 30 escaped from the face 74 on said slide the tumbler is partially returned until the projecting portion 72 engages the lower end of the depending lug 68 as will be seen by the dotted positions of said members in Fig. 3. 35 The key 59 may then be withdrawn as it is of no further use, it being impossible to return the slide to its normal position by means of said key for the reason that should said key be revolved in the opposite direction to that indicated by the arrow "a" the extremity of the web of said key will engage the end 77 of the straight portion 76 of the tumbler instead of said straight portion, thereby preventing the rotation of said key 40 in that direction. Should the bolt 16 be at the opposite end of its throw the key 59 will be rotated in the opposite direction and the web thereof engage the face 78 at the opposite end of the recess rather than the face 74 to move said slide until the projection 45 84 engages the inner face 19' of the end 19 of the bolt, or should an attempt be made to return the slide 61 to its normal position the web of said key would strike the opposite end 79 of the straight portion 76 and thus prevent the depressing of the tumbler. During the operation of the slide 61 by means of the key 59 the pin 52 is moved to its intermediate position as indicated by the dotted circles 80, thus moving the indicator 55 but half of its throw, consequently displaying half red and half white instead of all red or all white which indicates that the room has been properly cared for by the attendant and in readiness for the occupant

thereof to enter which he or she may do by unlocking the regular lock of the door and after entering the lock 16 is reciprocated to lock said door upon the inside preferably by the same key. During this movement of the bolt 70 the slide 61 will be moved together with said bolt on account of the friction between the projecting portion of the tumbler and the depending lug 68 of said bolt until the end 81 is moved into contact with the end 75 82 of the casing 8 which prevents further movement of said slide, but permits the bolt to continue until said depending lug 68 alines with the notch 67, which is its normal position. Should said bolt be moving in 80 the opposite direction from that just described the end 85 thereof will engage the corresponding end 86 of said casing and move said slide in the opposite direction to that mentioned. As hereinbefore stated any 85 movement of the bolt 16 subsequently to the setting of the indicator in its intermediate position will cause said indicator to be returned to its normal position by the means hereinbefore described.

The bolt 16 is operable only from within the room with the result that should anything happen to the occupant of the room and he be unable to unlock the door any one wishing to render him assistance would be 90 prevented from entering said room. For this purpose a keyhole 87 is provided in the door "A" alining with the cylindrical hole 30 and extending to the outside of said door, said hole 87 being normally closed or sealed 95 by a projecting portion 88 preferably formed upon the casing 37 which may be chipped off along the line b-b Fig. 6 by a cold chisel or some like instrument when the case so demands, permitting a master key 100 89, as indicated in dotted lines Fig. 4, to be inserted therethrough to rotate the cylindrical member 25, said key being the same for all locks of this type.

When it is desired to arrange the lock for a door swinging in the opposite direction from that referred to the cylindrical member, which is identical in construction at opposite ends, is removed and placed end for end, thus bringing the lateral projecting portion 26 upon the opposite side of the vertical plane referred to or in the position indicated in dotted lines in Fig. 3, although at this time the slot 31 will remain as in full lines in said figure, while the end 17 of the bolt will be protruding from the casing 8 rather than the end 19. It will also be necessary to withdraw the connecting rod or key 45 from the slot 48 and the indicator tumbler 50 rotated to aline the other of said slots 48 with said rod in order that the white differentiating characters may be presented to view at the openings 42 in the casing 37, thus putting said lock in a condition to be operated as hereinbefore described.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific application herein shown, but 10 that extensive deviations from the illustrated form or embodiment of the invention may be made without departing from the principles thereof.

Having thus described my invention what 15 I claim and desire by Letters Patent to secure is:

1. A lock having, in combination, a bolt, a slide mounted on said bolt, a tumbler adapted to normally prevent a movement of 20 said slide relatively to said bolt, and an indicator operatively connected with said slide adapted to indicate the locked and unlocked positions of said bolt, said indicator being arranged to operate independently of said 25 bolt.

2. A lock having, in combination, a bolt, means to operate said bolt, a slide mounted on said bolt adapted to normally move with said bolt, an indicator operatively connected 30 with said slide, said indicator adapted to indicate the extreme positions of said bolt, said slide adapted to be moved relatively to said bolt to present a different character from that indicating the extreme positions 35 of said bolt, and means rendered operable by a subsequent movement of said bolt adapted to return said slide to its normal position.

3. A lock having, in combination, a bolt, 40 a slide mounted on said bolt and movable relatively thereto, means to lock said slide on said bolt to prevent said relative movement, means operatively connected with said slide adapted to indicate the extreme positions 45 of said bolt, said means also adapted to indicate the position of said slide when the same has been moved relatively to said bolt.

Copies of this patent may be obtained for five cents each, by addressing the "Commissioner of Patents, Washington, D. C."

4. A lock having, in combination, a bolt, a slide mounted on said bolt and movable 50 relatively thereto, a tumbler adapted to normally prevent a relative movement between said slide and said bolt, and an indicator adapted to indicate the positions of said bolt and the positions of said slide on said bolt. 55

5. A lock having, in combination, a bolt, a slide mounted on said bolt and movable relatively thereto, a tumbler adapted to engage said slide and lock the same on said bolt, a spring adapted to yieldingly retain 60 said tumbler in engagement with said slide, an indicator operatively connected with said slide adapted to indicate the movement of said slide relatively to said bolt.

6. A lock having, in combination, a bolt, a slide mounted on said bolt and movable relatively thereto, stops on said bolt adapted to limit the movements of said slide relatively thereto, and an indicator operatively connected with said slide. 70

7. A lock having, in combination, a bolt, a slide mounted on said bolt and adapted to be moved relatively thereto, an indicator operatively connected with said slide, means to reciprocate said bolt and said slide, means to reciprocate said slide relatively to said bolt, and means rendered operative by a subsequent movement of said bolt adapted to return said slide to its normal position on said bolt. 75

8. A lock having, in combination, a bolt, a slide mounted on said bolt, a tumbler adapted to normally prevent a movement of said slide relatively to said bolt, means adapted to move said slide in one direction 80 on said bolt, and means rendered operative by a subsequent movement of said bolt adapted to move said slide in the opposite direction on said bolt.

In testimony whereof I have hereunto set 90 my hand in presence of two subscribing witnesses.
